CARTON OR SIMILAR ARTICLE

Thomas M. Biallo, 430 E. 56th St.,
New York, N.Y. 10022

Original design application May 20, 1968, Ser. No.
12,013. Divided and this application Sept. 29, 1969,
Ser. No. 19,795

Term of patent 14 years

Int. Cl. D9—04

U.S. Cl. D9—230

FIG. 1 is a perspective view of a carton or similar article embodying my new design;

FIG. 2 is a side elevational view;

FIG. 3 is a front elevational view;

FIG. 4 is a bottom plan view;

FIG. 5 is a top plan view; and

FIG. 6 is a perspective view showing the top in a partially opened position.

This application is a division of design application Ser. No. D. 12,013, filed May 20, 1968.

I claim:

The ornamental design for a carton or similar article, substantially as shown and described.
